UNITED STATES PATENT OFFICE.

ALEXANDER T. KASLEY, OF MOORE, PENNSYLVANIA, ASSIGNOR TO WESTINGHOUSE ELECTRIC & MANUFACTURING COMPANY, A CORPORATION OF PENNSYLVANIA.

BLADE LASHING.

Application filed September 12, 1925. Serial No. 56,027.

My invention relates to elastic fluid turbines, more particularly to the blading thereof, and has for its object the provision of a lashing means for the blades which shall be simple of design, easy of application and which shall be effective to minimize vibration of the blading.

Apparatus made in accordance with my invention is illustrated in the accompanying drawings, forming a part of this specification, in which Fig. 1 is a fragmentary sectional view of a plurality of turbine blades having my improved lashing applied thereto; Fig. 2 is a view similar to Fig. 1 showing a modified form of my invention; Fig. 3 is a similar view showing a further modification of my invention; Fig. 4 is a plan view of a plurality of blades having still another modification of my invention applied thereto; and Fig. 5 is a longitudinal sectional view of the structure shown in Fig. 4.

As is well understood in the art to which my invention relates, turbine blades when subjected to strains incident to service are liable to vibrate and break due to vibration. In order to minimize vibration, some form of bracing means is usually applied, extending along a blade row and secured to each blade of a segment of blades by soldering, brazing or otherwise. While such a form of lashing is effective to minimize vibration, considerable labor is involved in applying it and, where the lashing is united to the blade by fusion of metal, it has been found in some instances to have a deleterious effect on the physical properties of the blades.

Furthermore, with lashing secured by whatever means to a series of blades, upon expansion and contraction of the blading and blade carrying element, there is an alternate stretching and crushing action between the blades and the lashing. This is due to the fact that radial expansion and contraction of the turbine parts increases and decreases the distances between adjacent blades in a row. The alternate stretching and crushing action between the blades and the lashing tends to fatigue the metal thereof and ultimately leads to breakage in many cases.

In accordance with my invention, I have devised a turbine blade lashing comprising members which are effective to dampen vibration of the blading by frictional engagement therewith. In the case of moving blades, the frictional engagement is secured by providing an element of the lashing of sufficient mass so that, when the turbine is operating, centrifugal force tends to hold it in tight frictional engagement with a cooperating blade. In the case of stationary blades, the unattached lashing element is preferably made of resilient material and is sprung into engagement with its cooperating blade. With this form of lashing, upon expansion and contraction of the turbine parts, the lashing members are free to compensate for changing distances between adjacent blades by sliding at the point of frictional engagement. At the same time the frictional engagement is sufficient to dampen vibration of the blading.

Referring now to the drawings for a better understanding of my invention I show in Fig. 1 at 10-10 a plurality of turbine blades having my improved lashing applied thereto. The lashing is comprised of individual members each having two head elements 11 and 12, said elements being joined together by a relatively thin neck element 13. The element 13 is made of lesser cross-section than the other two elements in order to minimize the resistance to motive fluid flow between the blades. The element 11 is inserted in a suitably formed hole in the blade 10 and may be permanently secured thereto by riveting before the blades are assembled. The member 12 is of suitable mass and is inserted in a hole 14 formed in its cooperating blade, the said hole being of sufficient size so that the member 12 slides freely therein.

When the lashing is applied as shown in Fig. 1, and having only one member 12, it is preferable to provide a double row of lashing and to secure the members 11 to alternate blades as shown. In this manner, each blade 10, in the process of manufacture, has attached thereto one of my improved lashing elements and is adapted to receive the member 12 of the lashing element attached

to adjacent blades. In operation the member 12 is held in firm engagement with its associated blade 10 by reason of centrifugal force in the case of moving blades.

5 Referring to Fig. 2 I show a form of my invention better adapted for stationary blades. The lashing here shown comprises an element 16 attached to a blade 17 in a manner similar to that shown for the element 11 of Fig. 1. In this instance the lashing element is made of resilient material, is bifurcated and extends to an adjacent blade where it is provided with an enlarged portion 18 which is sprung into the 10 blade and is engaged therewith by frictional contact due to the resiliency of the material employed. As in the case of the lashing illustrated in Fig. 1, it is preferable to apply the form shown in Fig. 2 in two rows and 15 secure the elements 16 to alternate blades.

Referring now to Fig. 3 I show another form of my invention applicable to moving blades and which is permanently attached to only one blade of a segment of blades. The 20 lashing here shown comprises an element 21 similar to the elements 16 and 11 shown in the previous embodiments and secured to a moving blade 22. Connected to the element 21 by a series of elements of relatively small cross-section 23-23 are a plurality of elements 24-24 similar to the elements 12 shown in Fig. 1 and which engage with their associated blades by frictional contact induced by centrifugal force. In accordance 25 with this modification of my invention I may only apply one row of lashing, though it will be obvious that a plurality of rows might be employed with equal advantage where required.

40 Referring to Figs. 4 and 5, I show a series of blades 26-26 having an outer and an inner series of holes 27-27 and 28-28 provided therein. The holes 27-27 and 28-28 are elongated, having the greater dimension 45 in the direction of motive fluid flow. Inserted in the holes 27 in the alternate spaces between adjacent blades in a row are individual lashing members comprising the elements 29 and 31 fitting freely into the holes 50 27-27 and joined together by a member 32 wider than the holes 27-27. The member 32 being wider than the holes in the blades serves to preserve the proper distance between the blades and holds the lashing members 55 in proper position. In the other alternate spaces between blades in a row a series of similar lashing members are inserted in the holes 28-28 so that the inner and outer series are applied in staggered relation. 60 When applied to moving blades the form of lashing here shown engages with the blades wholly by friction induced by centrifugal force.

65 From the foregoing it will be apparent that I have invented an improved turbine

blade lashing simple of design, easy of manufacture and which is effective to minimize blade vibration by virtue of frictional engagement with the blades.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. A turbine blade lashing comprising a member extending between adjacent blades in a row and means for engaging said member with a blade solely by friction.

2. A lashing for turbine blades comprising one member adapted to be secured to a turbine blade, a second member, means for engaging said second member with an adjacent blade by friction only, and a third member joining the first and second members.

3. A lashing for turbine blades comprising one member adapted to be secured to a turbine blade, a second member movable relatively to an adjacent blade, means for engaging said second member with said adjacent blade by friction, and a third member of relatively small cross-sectional area joining the first and second members.

4. The combination with a plurality of turbine blades in a row having holes provided therein for the insertion of lashing members, of lashing means for said blades extending between adjacent blades in a row, each of said lashing members being movable relatively to at least one blade, and means for engaging each lashing member with said one blade by friction induced by centrifugal force.

5. A lashing member for adjacent turbine blades in a row comprising a member adapted to be secured to a turbine blade, a second member of suitable mass inserted in a hole in an adjacent blade and movable therein, means for engaging the second member with said adjacent blade by frictional contact, and a relatively thin member joining the other two members.

6. In a turbine, a row of moving blades, an inner and an outer series of holes provided in said blades for the insertion of lashing members, lashing members secured each to one blade in the inner and outer series of holes in staggered relation and means for engaging said lashing members with adjacent blades in a row solely by friction.

7. In a turbine, a row of moving blades having aligned holes provided therein for the insertion of lashing members, lashing members inserted in the holes and extending

between adjacent blades in a row, said lashing members being secured to one blade and having means for engaging with another blade solely by friction due to centrifugal force.

8. In a turbine, a row of moving blades, a lashing member secured to one blade and

movable with respect to an adjacent blade, and means for engaging the lashing member with said adjacent blade by friction.

In testimony whereof, I have hereunto subscribed my name this twenty-sixth day of August 1925.

ALEXANDER T. KASLEY.
